UNITED STATES PATENT OFFICE

121,456

DESIGN FOR A SOUVENIR BODY BELT

Marion F. Masters, Brownwood, Tex.

Application May 23, 1940, Serial No. 92,542

Term of patent 14 years

To the Commissioner of Patents:

Be it known that I, Marion F. Masters, a citizen of the United States, residing at Brownwood, in the county of Brown and State of Texas, have invented a new, original, and ornamental Design for a Souvenir Body Belt, whereof the following is a specification, reference being had to the accompanying drawing, forming part thereof.

In the aforesaid drawing:

Fig. 1 is a front elevational view of a souvenir body belt showing my new design;
Fig. 2 is a rear elevational view thereof; and
Fig. 3 is an edge view thereof.

I claim:

The ornamental design for a souvenir body belt, as shown.

MARION F. MASTERS.
